UNITED STATES PATENT OFFICE.

JACOB B. HYZER, OF JANESVILLE, WISCONSIN.

VENTILATOR.

SPECIFICATION forming part of Letters Patent No. 496,784, dated May 2, 1893.

Application filed October 22, 1892. Serial No. 449,569. (No model.)

To all whom it may concern:

Be it known that I, JACOB B. HYZER, a citizen of the United States, and a resident of Janesville, in the county of Rock and State 5 of Wisconsin, have invented certain new and useful Improvements in Ventilators; and I do hereby declare that the following is a full, clear, and exact description of the invention, which will enable others skilled in the art to 10 which it appertains to make and use the same, reference being had to the accompanying drawings, which form a part of this specification.

My invention relates to an improved ventilator adapted to be used with dwelling houses, sleeping rooms, public halls, railroad cars and other places where it is desired to have the same perfectly and thoroughly ventilated.

20 The object of the invention is to provide an improved device of the above description which can be readily secured to the wall of a building whereby the foul and vitiated air in an apartment is allowed to escape and 25 pure, wholesome air to take its place.

The invention consists in the novel construction and combination of parts herein-after fully described and claimed.

In the accompanying drawings, Figure 1 is 30 an elevation of a ventilator constructed in accordance with my invention. Fig. 2 is a sectional view of the device detached. Fig. 3 is a perspective view of the upright or lug detached.

35 In the said drawings the reference numeral 1 designates a metallic box, adapted to be passed through an opening in the wall of a house, car or other structure. When used in a dwelling house it is preferably located underneath or above the window of the room which it is to be used in connection with. The outer end of this box is curved or rounded and is provided with an opening 2, leading to the atmosphere. Pivoted in this box intermediate of the ends thereof is a valve 4, consisting of a rectangular plate, the pivot pin 6 thereof passing through lugs thereon, near the outer end thereof. This valve is adapted to fall by gravity and close the ventilator. 45 At the inner end of the box is a valve consisting of a flat plate 7, pivoted at its center

to the edges of the side walls of the box. This valve is provided with an inwardly extending rod 8, passing through a lug 13, secured to one of the walls of the box and is 55 adapted to strike and open valve 4, when it is actuated. The journal or pivot pin 9, of valve 7, is provided with a double crank 10, one end of which is adapted to be grasped by the fingers to operate the same and the 60 other end is adapted to engage with a notched segment 12, secured to the box, so as to hold the valve in any position to which it may be adjusted.

The operation will be readily understood. 65 An opening is made in the building through which the ventilator is passed and secured in any convenient manner so that the opening in the outer end thereof will communicate with the atmosphere. When it is desired to open the ventilator to allow the foul and vitiated air to escape, the valve 7, is turned so as to open the same, when the rod 8 will strike the valve 4, opening the same and thus affording an egress for said air. The 70 throw of these valves can be regulated by adjusting the inner valve and it may be retained in its adjusted position by means of the crank and notched segment.

From the above it will be seen that I provide a very efficient device for the purpose intended, which is burglar-proof and also proof against unauthorized tampering with.

The outer end of the box may be provided with a wire gauze covering or screen to prevent access of insects and dust or dirt.

Having thus described my invention, what I claim is—

As an improved article a ventilator consisting of a metal box adapted to be passed through and be secured in an opening in the wall of a building or other structure, with its outer end projecting beyond said wall, said end being downwardly curved and provided with an opening in its under side, the 90 gravity valve located in said box intermediate of the ends and pivoted to the upper side thereof, the upright or lug secured to the under side of the box and provided with an aperture, the valve at the inner open end of the 95 box provided with a central transverse shaft journaled in the sides of the box, the double 100

crank secured to one end of said shaft, the
notched segment, and the inwardly extending
rod secured to the upper end of said valve,
passing through the aperture in the upright
5 or lug, and adapted to strike against and open
the gravity valve when the double crank is
actuated to open the valve at the inner end
of the box, substantially as described.

In testimony that I claim the foregoing as
my own I have hereunto affixed my signature to
in presence of two witnesses.

JACOB B. HYZER.
